UNITED STATES PATENT OFFICE.

KRISTIAN H. E. HÖYBY, OF ODENSE, DENMARK.

LAMP-BURNER.

SPECIFICATION forming part of Letters Patent No. 225,524, dated March 16, 1880.

Application filed January 19, 1880.

To all whom it may concern:

Be it known that I, KRISTIAN H. E. HÖYBY, of the city of Odense, in the Kingdom of Denmark, have invented certain new and useful Improvements in Lamp-Burners; and I do hereby declare that the following is a full, clear, and exact description of the invention, which will enable others skilled in the art to which it appertains to make and use the same, reference 5 being had to the accompanying drawings, which form a part of this specification.

My invention has relation to that class of lamp-burners (for petroleum and other lamps that require a chimney and globe) which are provided with means for raising or elevating the collar which supports the chimney and globe above the wick, so that a match may be applied to this for the purpose of ignition without having to remove the globe and chimney; and it consists in the improvements hereinafter described, and particularly pointed out in the claim.

In the drawings hereto annexed, Figure 1 is a vertical section of my improved burner. Fig. 2 is a similar view, showing the chimney-collar and globe holder or gallery in their elevated position, ready for the ignition of the wick. Fig. 3 is a perspective view of the spur-wheel and spring-catch for operating the rack-bar; and Fig. 4 is a similar view of the sliding sleeve with its chimney-collar and rack-bar, the globe-gallery having been removed.

A is the wick-tube, which may be of any approved construction, and in the present illustration of my invention is bifurcated at its lower end, to be used with a flat wick, which is bent in its passage through the wick-tube into a cylindrical shape by its two edges meeting, in like manner to the wick of an Argand 35 burner.

B is the wick-raising wheel, and C is the burner-basket, which is screwed upon the lower end of the wick-tube above its collar b, as clearly shown in the drawings. This basket C has an annular flange or collar, c, at its upper end, surrounding the central wick-tube, which is provided with a laterally-projecting tube or sleeve, d, through which is inserted the shaft of the spur-wheel D.

E is a spring, the lower end of which is secured in the lower inner end of the basket C,

while its upper end has a projection or arm, e, which extends up to one side of the spur-wheel D, and is provided at its upper end with an inward-projecting lip, f. This part e of spring 55 E impinges upon the rack-guide g, which is attached to and projects inward from the upper collar, c, of the basket C.

F is a cylindrical sleeve, which is inserted upon another stationary cylindrical sleeve, A', 60 that surrounds the wick-tube A, and slides thereon.

Upon the upper part of sleeve F are affixed the concentric chimney-collar H and globe-gallery I, and the said sleeve F is further provided with the rack-bar G, which meshes with spur-wheel D.

Rack-bar G is guided by the inwardly-projecting guide piece or arm g, reference to which has already been made, and has a stop or catch, 70 h, at its lower end.

The lip f of spring E bears against the front side of the rack-bar with sufficient friction to support sleeve F, with the chimney and globe, in its elevated position, as shown in 75 Fig. 2, and performs the further office or function of preventing the rack-bar from being raised too high or out of gear with its spur-wheel by bearing against the stop h at the lower end of the bar. Besides this, the top of 80 spring E serves as a journal or support for the inner end of the shaft of the spur-wheel D, which works in a recess made in the upper end of the spring, as shown more clearly in Fig. 2.

The stationary cylindrical sleeve A', which surrounds the wick-tube, as well as the sliding sleeve F, are made of skeleton-work, or constructed with suitable openings to admit a sufficiency of atmospheric air to the inner part 90 of the burner where combustion takes place, and the chimney-collar H has a downwardly-projecting annular flange, k, which, when the collar with its sleeve is in its depressed or lowered position, will fit snugly into collar c 95 of the basket C.

Having thus described my invention, I claim and desire to secure by Letters Patent of the United States—

In a lamp-burner of the described class, the 100 combination of the basket C, having collar c, spur-wheel D, guide g, and spring E, provided

with the arm *e* and lip *f*, stationary sleeve *A'*, encircling the wick-tube *A*, and sliding sleeve *F*, carrying the chimney-collar *H* and globe-gallery *I*, and provided with the rack-bar *G*, having stop *h*, all constructed and combined to operate substantially in the manner and for the purpose herein shown and set forth.

In testimony whereof I have signed my name to the foregoing specification in the presence of two subscribing witnesses.

KRISTIAN HANSEN ENGERMAND HÖYBY.
